(57) **CLAIM**

The ornamental design for a dashboard documentation holder, as shown and described.

DESCRIPTION

FIG. 1 is a right frontal perspective view of a dashboard documentation holder illustratively incorporating my present design, shown in a closed configuration with a lid portion covering a documentation compartment of a body portion; FIG. 2 is a left side elevational view of the dashboard documentation holder as shown in FIG. 1; FIG. 3 is a right side elevational view of the dashboard documentation holder as shown in FIG. 1; FIG. 4 is a front elevational view of the dashboard documentation holder as shown in FIG. 1; FIG. 5 is a rear elevational view of the dashboard documentation holder as shown in FIG. 1; FIG. 6 is a top plan view of the dashboard documentation holder as shown in FIG. 1; FIG. 7 is a bottom plan view of the dashboard documentation holder as shown in FIG. 1; and, FIG. 8 is a left frontal perspective view of the dashboard documentation holder of FIG. 1, but shown in an open configuration, with the lid portion raised to reveal the documentation compartment of the body portion. The features and environment represented in broken lines are shown for illustrative purposes only and form no part of the claimed design.
